UNITED STATES PATENT OFFICE.

HARRY T. LOOMIS, OF BROOKLYN, NEW YORK.

DESIGN FOR A TEXTILE FABRIC.

51,419.

Specification for Design.

Patented Oct. 23, 1917.

Application filed September 6, 1917. Serial No. 190,088. Term of patent 3½ years.

To all whom it may concern:

Be it known that I, HARRY T. LOOMIS, a citizen of the United States, and residing in the borough of Brooklyn, in the city of New York, county and State of New York, have invented a new, original, and ornamental Design for a Textile Fabric, of which the following is a specification, reference being had to the accompanying drawing, forming part thereof.

The figure is a plan view of a portion of textile fabric showing my new design.

I claim:

The ornamental design for a textile fabric, as shown.

HARRY T. LOOMIS.

Witnesses:

C. E. MULREANY,
H. E. THOMPSON.
